UNITED STATES PATENT OFFICE.

VICTOR J. SHEPARD, OF PITTSBURGH, PENNSYLVANIA, ASSIGNOR TO WESTINGHOUSE ELECTRIC & MANUFACTURING COMPANY, A CORPORATION OF PENNSYLVANIA.

DRIVING BOX.

Application filed November 7, 1922. Serial No. 599,546.

My invention relates to driving boxes, such as are employed for journalling the side frames of locomotives or cars to the driving or carrying axles, more especially to outside journal boxes adapted for use on locomotives where the space between the side frames is occupied by the driving-gear mechanism.

It is among the objects of this invention to provide a driving box comprising a minimum number of parts that shall be readily accessible for the removal of the bearing member and which shall be of simple and relatively inexpensive construction.

Driving boxes heretofore employed comprise substantially box-shape members which are movably mounted between the pedestal jaws of the side-frame members having wearing shoes of a suitable bearing material interposed therebetween. The boxes are usually provided with flanged body portions which engage the sides of the shoe members to maintain alinement and to prevent binding with the axle members. Such flanged box was held in position by a pedestal binder which was adapted to be removed and the box was subsequently removed by raising the side frame above the wheel axle to permit the box to slide down or by dropping the wheels and boxes.

My present invention is directed to driving-box structures which are adapted to be mounted in, or removed from, the side frame members without necessitating the dismantling thereof, and such boxes are provided with suitable retaining blocks for mounting the spring saddles and crown brasses or bearing blocks, all of which are held in their respective positions by a plurality of dowel pins. The crown brass is removed by raising the saddle above the retaining block so that the dowel pins are out of engagement with the bearing block which is then readily removed by a suitable hook or the like.

In the accompanying drawing, constituting a part hereof, and in which like reference characters designate like parts,

Figure 1 is a front elevational view taken along the line I—I of Fig. 3, of a drive box embodying the principles of this invention mounted between a pair of pedestal jaws of a side-frame member;

Fig. 2 is a vertical sectional view taken along the line II—II of Fig. 1; and

Fig. 3 is a plan view, partially in section,

taken along the line III—III of Fig. 1, showing the relative positions of the various assembled parts.

Fig. 4 is a view partially in section and partially in elevation taken along the line IV—IV, Fig. 6.

Fig. 5 is a similar view taken along the line V—V, Fig. 6, and

Fig. 6 is a vertical sectional view taken along the line VI—VI, Fig. 1.

The journal-box structure consists of a substantially box-shape casing 1 provided with extending flange portions 2 which are in sliding engagement with the shoes 3 disposed around the pedestal jaws 4. The upper portion of the casing is provided with a projection 5 having a recess 6 in which a leg of a spring saddle 7 is mounted. The saddle 7 supports a spring 8 which is fastened thereto by a band 9. A crown brass or bearing block 10 is attached to the portion 5 of the casing by means of a plurality of dowel pins 11 which are secured to the spring saddles 7 and extend through the casing into the bearing block 10.

A rectangular flange member 12, having its longest dimension corresponding to the overall length of the box 1 from the ends of the flanges 2 and having its shorter dimension slightly less than the distance between the shoes 3 of the pedestal jaws, is secured to the box 1 on the rear portion thereof by a retaining ring 13 which is pressed on the casing 1. The rectangular member 12 constitutes the inner flange member of the box which engages the pedestal shoe 3 to maintain alinement of the box member with the frame.

The drive box is adapted to vertical movement between the pedestal jaws and is further journalled to a wheel axle 15 on which it is supported by the crown brass or bearing block 10. The load of the vehicle is supported through the drive springs 8, spring saddle 7 and the casing 1 on the axle 15. The drive box is retained between the pedestal jaws 4 by a pedestal binder 16 (Fig. 1).

If it is desired to remove the bearing block 10, the spring saddle 7 is raised to disengage the dowel pins 11 from the bearing 10 which may then be readily withdrawn in a suitable manner, as by inserting a screw bolt into the threaded opening 17. If it is desired to remove the entire box, it will not be necessary to raise the entire frame member but may be

accomplished by releasing the retaining ring 13 and moving the rectangular flange member 12 angularly 90° so that its short side corresponds to the space between the pedestal shoes 3 which permits of removing the box by pulling it straight forward from the wheel axle 15.

It will be evident from the above description of my invention that driving boxes 10 formed in accordance therewith constitute a simple and inexpensive structure all of the parts of which are readily accessible for removal to be repaired or replaced. The structure herein employed does not require the 15 use of screw bolts or the like and is readily assembled in its operating position on a wheel-axle bearing without the difficulty of fitting the members between the pedestal jaws which has heretofore been experienced. 20 Although I have described a specific embodiment of my invention, it will be obvious to those skilled in the art that various modifications may be made in the details of construction without departing from the principles herein set forth. For instance, the general shape and design of the box and the various accessory parts may be altered to accommodate any specific service requirement and the method of mounting the driving spring upon the spring saddle and the latter upon the retaining block may be altered in any manner to be consistent with the retention of the members by means of the load applied thereto.

35 I claim as my invention:

1. A locomotive driving box comprising a substantially box-shape casing, an integral projection formed thereon, a bearing block, and a spring saddle, said saddle, bearing block and projection being secured by a plurality of dowel pins.

2. A locomotive driving box comprising a substantially box-shape casing having a flange portion adapted to engage one side 45 of the pedestal shoes and a rectangular flange member mounted on the rear of said box to engage the other side of said shoes.

3. A locomotive driving box comprising a substantially box-shape casing having a 50 flange portion adapted to engage one side of the pedestal shoes and a rectangular flange member mounted on the rear of said box to engage the other side of said shoes, said rectangular member being angularly movable with respect to said casing.

4. A locomotive driving box comprising a substantially box-shape casing having a flange portion adapted to engage one side 60 of the pedestal shoes and a rectangular flange member mounted on the rear of said box to engage the other side of said shoes, said rectangular member being angularly

movable with respect to said casing and secured thereto by a ring.

5. A locomotive driving box comprising 65 a substantially box-shape casing having a flange portion adapted to engage one side of the pedestal shoes, an integral projection formed thereon, a bearing block movably secured to said projection, a rectangular flange member mounted on the rear end of 70 said box, and a retaining ring for securing said flange to said box.

6. A locomotive driving box comprising a substantially box-shape casing having a 75 flange portion adapted to engage one side of the pedestal shoes, an integral projection portion formed on said casing, a bearing block movably secured to said projecting portion, a rectangular flange member mounted on the rear end of said box, and a retaining ring for securing said flange to said box, said rectangular member being angularly 80 movable with respect to said casing.

7. A locomotive driving box comprising a substantially box-shape casing having a flange portion adapted to engage one side 85 of the pedestal shoes, a projecting body portion formed integrally on said casing, a bearing block movably secured to said projecting portion, a spring saddle mounted on said retaining block, a rectangular flange member mounted on the rear end of said box and a retaining ring for securing said flange to 90 said box, said rectangular member being angularly movable with respect to said casing.

8. A locomotive driving box comprising a substantially box-shape casing having a flange portion adapted to engage one side of the pedestal shoes, an integral projection formed on said casing, a bearing block movably secured to said projection, a spring saddle mounted on said projection, a rectangular flange member mounted on the rear end of 100 said box and a retaining ring for securing said flange to said box, said rectangular member being angularly movable with respect to said casing, said saddle, casing and bearing block being connected by a plurality 105 of dowel pins secured in said saddle.

9. A locomotive driving box comprising a substantially box-shape casing having a flange portion, a cover hinge thereon, an integral projection formed thereon, a spring saddle mounted on said projection, a bearing block removably secured thereto, a flange member mounted on the rear of said box and a ring for securing said flange member to said box, said flange being angularly 115 movable on the said box.

In testimony whereof, I have hereunto subscribed my name this 24th day of October, 1922.

VICTOR J. SHEPARD.
